UNITED STATES PATENT OFFICE

2,023,334

AEROPLANE

Louis Marmonier, Lyon, France

Application March 2, 1932, Serial No. 596,322
In France March 10, 1931

5 Claims. (Cl. 244—14)

The purpose of the present invention is the application of tilting propellers to aeroplanes of the ordinary type so that they can be utilized either as propellers to drive the aeroplane and maintain its relative speed, or simultaneously as driving and supporting propellers in order to support the aeroplane during its descent, to facilitate landing or to enable it to rise without the necessity of setting the aeroplane at a dangerous angle of approach. The device is therefore a compromise between the ordinary aeroplane and the helicopter, since it utilizes the respective properties of each of these machines.

The presence, however, of tilting propellers on an aeroplane presents two distinct problems—a gyroscopic problem and an aerodynamic problem. The conditions under which these propellers are employed are not the same as those of an aeroplane of the present type where they are placed in a fixed position, and where their tractive effort is exercised always in the same direction and at the same point of the aeroplane.

When the aeroplane is in the line of flight the tilting propellers are placed in their normal position, their driving force being exercised exclusively in the direction of flight of the machine and without limitation of speed resulting from supplementary apparatus as is the case with helicopters or those of the type known as "autogir". In order to cause the aeroplane to rise or descend, the propellers are set more or less towards the zenith in order that their tractive effort may contribute not only towards the maintenance by the wings of all their carrying power but to increase the support of the aeroplane in a proportion corresponding to their inclination from the zenith and to their speed of rotation.

To modify the angle of the propellers in relation to the supporting planes of the aeroplane, several methods can be employed. That which appears to be the most simple and the easiest to fit to aeroplanes consists in tilting the motor unit together with its propeller, the axis of rotation being arranged so that their masses are balanced.

To prevent these tilting propellers, which constitute powerful gyroscopes, from affecting the lateral and longitudinal stability of the aeroplane when they are tilted, they are—and these are the principal characteristics of the invention—

- 50 1. Coupled in pairs and rotate at equal speeds but in opposite directions to one another;
2. For each pair, mounted so as to pivot on a rigid frame, and are joined by an appropriate device so that they tilt simultaneously under the action of a single force.

Further, these propellers, which can be mounted in line one behind the other are staggered, are so placed in the aeroplane that their centre of tractive effort passes through the centre of gravity or on the perpendicular of the centre of gravity of the machine and that this centre of gravity is itself on the longitudinal axis of the buoyancy centres of the supporting wings of the aeroplane which are placed in the same plane and connected by fuselages.

The invention will be quite clear from the supplementary description which follows and from the attached drawing, which are of course given especially as explanatory documents.

Figure 1 shows a diagrammatic view of a gyroscope mounted on a rigid frame, in unstable equilibrium, and under the action of the tilting force.

Figure 2 represents two gyroscopes with the same inertia, rotating in opposite directions and mounted on a rigid frame, and in unstable equilibrium, these gyroscopes being connected together by a coupling and subjected to the action of the same tilting couple.

Figure 3 represents the same arrangement as the above, the gyroscopes being in a different position and subjected to the action of a single checking force.

Figure 4 shows a small type helicopter aeroplane with two tilting propellers to which the arrangement is adapted.

Figure 5 shows the height control applied to the helicopter aeroplane and consisting of two compensated planes which balance one another.

In Figure 1, the gyroscope *a* is actuated by a motor mounted in a cradle *1*. This cradle pivots on a frame *2*, which is in a state of unstable equilibrium. This gyroscope rotates in the direction of the arrow *3* and can be tilted in its frame by the action of lever *4*. If this lever can produce a force *5*, assuming that this force has a point of application, the point *m* of the gyroscope *a* being acted on by force *m'* moves to *m''* in consequence of its rotation in the direction of the arrow *3*. The frame *2* then pivots in the direction of the arrows *6* and *7* and tilts in the direction of the arrows *8* and *9* under the influence of the force *5*.

Consequently, an aeroplane provided with only one tilting propeller, would exert not only a very appreciable tilting force, since this would have to overcome all of its gyroscopic inertia, but, owing to this tilting, the aeroplane would be liable to slip and its longitudinal equilibrium would be endangered.

In Figure 2, which represents two gyroscopes

coupled together and rotating in opposite directions, gyroscope *b* in the direction of arrow 10 and gyroscope *c* towards arrow 11, these gyroscopes are tilted under totally different conditions, provided that the tilting is caused by one and the same couple and has exactly the same amplitude. To do this, the two gyroscopes *b* and *c* are both actuated by lever 12 through a mechanical connection 32, so that their planes of rotation remain always parallel. When the couple 13 is produced by this lever, the point *n* of gyroscope *b* is caused to move to *n'*, which would cause the rigid frame 14 to pivot in the direction of the arrows 15 and 16, if the gyroscope *c* did not react in the opposite direction towards arrows 17 and 18, for the point *o* moves to *o'*. These precession couples act in opposite directions, their value being equalized. Since they are produced simultaneously on a rigid frame, they oppose one another in this frame and in the connection between the gyroscopes. The respective inertias of the two gyroscopes therefore annul one another.

Figure 3 illustrates the same arrangement as Figure 2, the gyroscopes *b* and *c* being in a different position after tilting. To move them back to their original position lever 12 is moved in the direction of arrow 19 producing on the gyroscope *b* a precession couple 20 and 21 to which is opposed a couple 22 and 23 of the same value and caused by gyroscope *c*. These couples annul one another in the rigid frame 14 and the force required to carry out this operation is practically nil.

From this explanation, it will be evident that when two tilting propellers coupled together by a connection which makes them act together and maintain their parallel planes of rotation, are fitted to an aeroplane, if these propellers rotate in opposite directions at the same speed, relatively no force is required to tilt them and this can be done by the pilot by a single operation.

On the basis of this very interesting property, the helicopter aeroplane represented in Figure 4 has been developed, the same arrangements being applicable to large machines with multiple propellers coupled in pairs. In this machine the two tilting propellers 24 and 25 rotate in opposite directions as shown by arrows 26 and 27, their speeds being equal, as nearly as possible, to facilitate the tilting. In the case shown in the drawing the propellers are situated in line on the aeroplane; they could equally well be staggered. When the aeroplane is in its line of flight the tilting propellers are in their normal position as driving propellers. They tilt in the direction of the arrows 28 and 29 to give support to the aeroplane during ascent and descent and also in case of loss of speed.

The engines which drive the propellers and tilt with them are mounted in the cradles 30 and 31 which can pivot. These cradles, which consist of welded tubing or of light channel-steel, turn in bearings mounted on the two carlings of the aeroplane. Their shafts are carefully balanced so that the weight of the engine counterbalances that of the propeller. These two cradles are coupled together by mechanical means, that shown in the drawing being merely typical. This can be modified to suit the aeroplane and the arrangement of the propellers. The connection in Figure 4 comprises: two levers mounted on the cradle shafts 30 and 31, these levers being coupled together by the rod 32 which couples together the two propellers 24 and 25.

The propellers are tilted by a pedal 33 operated by the pilot through the shaft 34 and rod 35, their return to the driving position being effected by spring 36. This pedal control can, if desired, be assisted by a vacuum servo-motor operated by the foot pedal and mounted on one of the propeller engines, this servo-motor being similar to those used for motor-car brakes. Compressed air would be employed in the case of large aeroplanes or when an automatic stabilizer is fitted.

The handle 37, in addition to operating the compensated and balanced height controls 38 and 39 and the adjustment of the wings, also serves in known manner to control the direction of the aeroplane.

These various operations could equally well be carried out by an automatic stabilizer.

On the other hand, the tractive centre of the propellers passes through the centre of gravity *G* of the machine so that the actual wing support 20 will not be affected by the change in direction of propulsion of the propellers. The centre of gravity of the aeroplane lies on the longitudinal axis of the buoyancy centres of the supporting wings.

Moreover, the profile of the propeller blades is such that they can act simultaneously for driving and supporting. This arrangement could also be applied in all cases in conjunction with a speed-loss indicator and vane for registering 30 side winds.

Another characteristic of this helicopter aeroplane consists in the positions in the aeroplane of the pilot and the passengers, who are placed at the back for increased safety. In this position they are isolated from the engines, propellers, and from the petrol tanks, etc. The supervision of the machine and correction of the flight in relation to the horizon are facilitated and landing is rendered easier since the pilot, being able 40 to see the track, can manoeuvre correctly. Furthermore, this arrangement makes it possible to fit an automatic parachute 40 on the aeroplane which is caused to open out instantaneously by the speed of the aeroplane. Also this can in case 45 of accident be used, even at the last minute.

On the other hand, this helicopter-aeroplane being auto-stable by its construction, in consequence of the large distance between the supporting wings, the longitudinal governor will necessitate planes of large dimensions so that the adjustment of the aeroplane may be instantaneous. This operation is difficult for the pilot and to reduce the force required for it the height control consists of movable planes of which one 39 is 55 mounted in front of the aeroplane on the front of the wing and the others 38 at the back. These planes, connected to the handle 37 by rods 41 and 42, are compensated and balance one another. When the pilot operates the handle 37 in order 60 to direct his machine, he must overcome the couple *p'* which is caused by the resistance of the air currents on plane 38 which make the couple *p*. On the other hand, this couple will be compensated by couple *q'* resulting from couple *q* 65 acting on plane 39. It will then be possible to fit to the helicopter-aeroplane planes sufficiently large to allow the height control to act.

The landing speed of the helicopter-aeroplane can be increased while in flight and so increase 70 the sensitiveness of the machine.

What I claim and desire to secure by Letters Patent of the United States is:—

1. A helicopter aeroplane having transversely extending front and rear supporting planes, 75

longitudinally extending frame members located at opposite sides of the aeroplane and connecting the front and rear supporting planes and spaced apart to provide a central propeller receiving space open throughout the entire length of said frame members, a pair of tilttable propellers arranged in tandem within said central open space and having counterbalancing motors, propeller and motor supporting means comprising transverse cradles journaled at their ends on the frame members and constituting transverse axes to permit pivotal movement of the propellers and their motors, and means for coupling the cradles for simultaneously tilting the propellers and motors on their transverse axes to arrange the propellers in either their horizontal or vertical positions.

2. A helicopter aeroplane having transversely extending front and rear supporting planes, longitudinally extending frame members located at opposite sides of the aeroplane and connecting the front and rear supporting planes and spaced apart to provide a central propeller receiving space open throughout the entire length of said frame members, a pair of tilttable propellers arranged in tandem within said central open space and having counterbalancing motors, propeller and motor supporting means comprising transverse cradles journaled at their ends on the frame members and constituting transverse axes to permit pivotal movement of the propellers and their motors, and means for coupling the cradles for simultaneously tilting the propellers and motors on their transverse axes to arrange the propellers in either their horizontal or vertical positions, said propellers being rotatable in opposite directions so as to balance their gyroscopic effects during the tilting operation.

3. A helicopter aeroplane having transversely extending front and rear supporting planes, longitudinally extending frame members located at opposite sides of the aeroplane and connecting the front and rear supporting planes and spaced apart to provide a central propeller receiving space open throughout the entire length of said frame members, a pair of tilttable propellers arranged in tandem within said central open space and having counterbalancing motors, propeller and motor supporting means comprising transverse cradles journaled at their ends on the frame members and constituting transverse axes to permit pivotal movement of the propellers and their motors, the propellers being rotatable in opposite directions with the front propeller located in front of its pivotal axis when in a vertical position and the rear propeller located in rear of its pivotal axis when in its vertical position, and means for coupling the propellers and for simultaneously swinging the same about their

axes whereby when the propellers are moved to a horizontal position, the front propeller will be located above its pivotal axis and the rear propeller will be located below its pivotal axis, thereby balancing their gyroscopic effects during the 5 tilting operation.

4. A helicopter aeroplane having transversely extending front and rear supporting planes, longitudinally extending frame members located at opposite sides of the aeroplane and connecting the front and rear supporting planes and spaced apart to provide a central propeller receiving space open throughout the entire length of said frame members, a pair of tilttable propellers arranged in tandem within said central open space 15 and having counterbalancing motors, propeller and motor supporting means comprising transverse cradles journaled at their ends on the frame members and constituting transverse axes to permit pivotal movement of the propellers and their 20 motors, the propellers being rotatable in opposite directions with one propeller located in front of its pivotal axis when in a vertical position and the other propeller located in rear of its pivotal axis when in its vertical position, and means for 25 coupling the propellers and for simultaneously swinging the same about their axes whereby when the propellers are moved to a horizontal position, the first propeller will be located above its pivotal axis and the second propeller will be located below its pivotal axis, thereby balancing their 30 gyroscopic effects during the tilting operation.

5. A helicopter aeroplane having transversely extending front and rear supporting planes, 35 longitudinally extending frame members located at opposite sides of the aeroplane and connecting the front and rear supporting planes and spaced apart to provide a central propeller receiving space open throughout the entire length of said 40 frame members, a pair of tilttable propellers arranged in tandem within said central open space along the longitudinal axis of the aeroplane and having their center of traction at the center of gravity of the aeroplane and having counterbalancing motors, propeller and motor supporting means comprising transverse cradles journaled at their ends on the frame members and constituting transverse axes to permit pivotal movement of the propellers and their motors, and 50 means for coupling the cradles for simultaneously tilting the propellers and motors on their transverse axes to arrange the propellers in either their horizontal or vertical positions, said propellers being rotatable in opposite directions 55 so as to balance their gyroscopic effects during the tilting operation.

LOUIS MARMONIER.
